ENGINE CARBURETOR WITH A CHOKING AND PRIMING CONTROL

Ralph S. Evinrude, Milwaukee, Wis., assignor to Outboard, Marine & Manufacturing Company, Waukegan, Ill., a corporation of Delaware

Application December 9, 1952, Serial No. 324,940

15 Claims. (Cl. 261—34)

This invention relates to an engine carburetor with a choking and priming control.

The invention is particularly intended for two-cycle engine carburetors of outboard motors, but its utility is by no means thus limited. The object of the invention is to provide a single control for both choking and priming which, in one continuous movement carried to a position for effecting maximum choking, will thereupon inject priming fuel, desirably from the outside of the carburetor through an opening in the choke valve. The control desirably comprises a reciprocable handle which, during a part of its stroke, controls the choke only. Only after the handle is moved beyond normal choking range does it effect priming.

In the priming operation, I desirably employ a valveless pump comprising a displacement plunger which moves through one seal toward another. In open communication between the two seals, the path of the plunger is completely exposed to the float chamber. Consequently, the normally retracted position of the plunger with respect to said other seal allows free access of fuel from the float chamber to the space beneath the last mentioned seal and in the path of the plunger. From this space opens the priming tube. As the plunger advances through the last mentioned seal, it traps fuel beneath it and its continued movement expels such fuel forcibly through the priming tube. I have thus provided a valveless pump or, in different aspects, a pump in which the plunger packing comprises the valve.

There is considerable advantage in operating the primer in the course of an extension of the same movement which operates the choke. Not only does it eliminate a separate control, but it also eliminates any need for conscious thought on the part of the operator, since both the choke and the primer have the function of providing extra fuel for starting and the requirement for priming is simply an enlargement of the requirement for choking. The greater the need for excess fuel, the greater will be the amount of fuel supplied, until, ultimately, raw fuel is injected directly into the carburetor as the primer becomes operative.

There is an important advantage also in effecting such injection from the exterior of the carburetor, the air passages being left entirely free of auxiliary ducts which might otherwise require valve control. It is customary to provide a small central opening in the choke valve for the admission of such air as is required to support combustion. The jet of priming fuel enters through the same hole.

It is important that the choke valve is closed impossibly through a tension spring and is unbalanced to be opened automatically by air pressure in the event the engine starts, thus enabling engine operation during the period required for the operator to restore the choke control to normal operating position.

In the drawings:

Fig. 1 is a side elevation of a carburetor embodying my invention.

2

Fig. 2 is a view taken in section on the lines 2—2 of Fig. 1, portions of the choke valve lever system being omitted.

Fig. 3 is a detailed view in perspective of choke valve operating parts.

Fig. 4 is a view taken in section on the line 4—4 of Fig. 2.

The carburetor chosen to exemplify the invention is a generally conventional type which, as best shown in Fig. 10, has a float bowl 5 containing a float 6 and from which passage 7 opens, subject to the control of needle valve 8, into the jet 9.

Jet 9 projects into the venturi throat 10 between the air inlet passage 11 and the throttle valve passage 12 at the outlet of the carburetor. While it forms no part of the present invention, it may be noted that the auxiliary needle valve 13 controls a port 14 opening into a mixing chamber 15 to supply thereto fuel derived through duct 16 from float chamber 5. Chamber 15 communicates with the carburetor passage 12 through ducts 17 and 18 lying at opposite sides of the position which is occupied by the throttle valve 20 when the latter is closed, as shown in Fig. 4. This arrangement is provided for the control of the idling operation of the engine to which the carburetor is applied, substantially all of the air required by the engine being forced to pass through duct 17 at the outer side of valve 20 into chamber 15 and out through duct 18 to the engine side of throttle valve 20 when the latter is closed. In chamber 15 the air will pick up its requirement of fuel as determined by the setting of needle valve 13. The throttle valve 20 is mounted on a rock shaft 21 having external control lever 22 best illustrated in Fig. 2.

In the admission passage 11 of the carburetor, there is another rock shaft 23 at a somewhat lower level which supports the normally open choke valve 24. This valve normally lies below the level of the jet tube 9, but as it closes toward the dotted line position shown in Fig. 4, it gradually shuts off the ingress of air, thereby increasing the extent to which engine vacuum is exerted on the jet tube. In the fully closed position of choke valve 24, substantially the only air admitted is received through the central port 25 in such valve. The rock shaft 23 upon which choke valve 24 oscillates is externally provided, as shown in Fig. 1, with an arm at 27 urged by tension spring 28 against the finger 29 of a lever 30. This lever is pivoted at 31 to a suitable boss on the carburetor body 32. A finger 33 at the upper end of lever 30 projects into an opening 34 in the manually operable control slide 35 to receive motion therefrom. This slide is rectilinearly reciprocable in ways provided by the guide bosses 36 and 37 on the carburetor body. In the course of its reciprocation it oscillates lever 30 thereby transmitting oscillatory closing movement to the choke valve 24 through spring 28.

The arrangement is such that the closing of the check valve is impositive. The spring has sufficient bias to hold the valve shut during the starting of the engine. As soon as the engine starts, the pressure of air entering the carburetor will open the valve sufficiently to provide adequate air for combustion during the interval required for the operator to retract the control 35. It will be observed that while the closing of the valve is impositive, the valve is positively required to open upon the retraction of control 35, motion being positively communicated through finger 29 of lever 30 to the rocker arm 27 on rock shaft 23.

The upper surface of the slide 35 has notches 38 and 39 engaged by a detent spring 40 to fix certain well defined positions of the slide. The notch 38 is deeper than the notch 39 to define the innermost position of the slide

regardless of the extreme position at which the slide comes to rest. The shallow notch 39 defines a position in which the choke valve is substantially closed, but the primer hereinafter described has not yet begun to operate.

In the normal retracted position of the slide in which it is illustrated in Fig. 1, the slide does not interfere with throttle valve 20. The throttle valve rock shaft 21 is extended toward the side of the carburetor shown in Fig. 1 and provided with a rocker arm 41 which normally clears slide 35 by reason of the recess 42 cut into the lower margin of the slide. However, for better performance of the particular engine for which this carburetor was designed, the contour of the slide at 42 is such that as the slide is withdrawn toward its extreme position, it will engage arm 41 to constrain the clockwise oscillation of the throttle valve rock shaft 21, as viewed in Fig. 1 (counterclockwise as viewed in Fig. 4), to somewhat open the throttle valve and thereby to admit enough air to pick up the relatively heavy charge of fuel injected by the priming mechanism presently to be described.

A cylinder boss 44 cast onto the side of the float bowl 5, as best shown in Figs. 1 and 2, carries a reciprocable priming plunger 45 which, in the normally retracted position of the manually operable slide 35 occupies the elevated position in which it is shown in Fig. 2. If the cylinder boss extends to a sufficiently high level, the plunger will need no upper packing. As shown, it is desirable to provide upper packing for the cylinder at 46 preferably in the form of an O-ring mounted in a groove undercut in the cylinder.

The cylinder portion 47 which is below the normally retracted position of plunger 45 opens into a pressure chamber 48 from which a duct 49 (Fig. 1) leads upwardly to the priming tube 50. The free end of this tube extends around in front of the inlet passage 11 of the carburetor and is directed as a nozzle toward the position of the aperture 25 in choke valve 24 in the closed position of the choke valve. The choke valve is always in its closed position before the priming mechanism acts. Consequently any fuel projected from the delivery end of pipe 50 is necessarily projected through port 25 into the carburetor inlet.

Intersecting the cylinder bore in which the plunger 45 is reciprocable is a passage 52 which opens directly from the carburetor bowl through the cylinder portion 47 into the displacement chamber 48. Upon reciprocation of plunger 45, the plunger first closes off communication between passage 52 and chamber 48 by entering the portion 47 of its cylinder. Here it preferably encounters an O-ring seal at 53, the O-ring being mounted in the undercut groove 54 in cylinder portion 47. Movement of the plunger to and from the O-ring acts like a valve to isolate one charge of fuel in chamber 48 from the float chamber 5, and subsequently to re-open communication of chamber 48 with float chamber 5 to receive a further charge of fuel.

The plunger is operated directly from the manually operable slide 35. For this purpose the slide is provided at its rear end with a cross pin at 55 which engages the slotted end of arm 56 on rock shaft 57. The forked arm 58 on rock shaft 57 engages a peripheral groove 59 in the upper end of plunger 45 so that, upon forward movement of slide 35 the plunger will be caused to move downwardly. The operation is as follows: the position of throttle valve 20 during the choking and priming operation is immaterial except for the provision made for opening the throttle valve slightly if it is fully closed during priming.

In starting, or any other condition when engine fuel is inadequate, the operator pulls forwardly on the handle of slide 35. The first effect of forward slide movement is to communicate oscillatory motion to the choke valve 24 through the lever 30 and arm 27 and intervening tension spring 28 in a direction to close the choke. At

the same time, downward motion is communicated to plunger 45 through rock shaft 57 and its arms 56 and 58. However, until the plunger engages the seal at 53, its motion will not effect any priming action.

Meantime, the choke valve will approach its completely closed position, as shown in dotted lines in Fig. 4. If, by that time, the fuel supply to the engine seems adequate, the operator will not continue to pull forwardly on the slide 35 but may return the slide to its initial position, thus relieving the choking action of choke valve 24. However, if the fuel supply is still inadequate for starting with the slide 35 advanced sufficiently far to close the choke valve, the operator will continue to pull forwardly upon the slide, whereupon plunger 45 will enter O-ring seal 53 and begin to displace fuel from chamber 48 through duct 49 and injection tube 50, whereby a stream of such fuel is injected through the port 25 directly into the carburetor. It will be remembered that at the time of such injection the cam surface of the slide 35 at 42 will act on arm 41 if the throttle valve is closed to effect at least a partial opening itself so that the engine will draw enough air to take care of the priming fuel thus injected.

Since the choke valve will have reached its extreme position before the priming operation occurs, lost motion is provided between finger 29 and arm 27 which permits the slide actuated lever 30 to advance independently of such arm against the tension of spring 28.

Movement of the control slide 35 from its advance position at the right in Fig. 1 toward its retracted position in which it is illustrated toward the left in Fig. 1, will first retract plunger 45 with concurrent contraction of spring 28 until finger 29 engages the outwardly turned end of arm 27. Thereupon, the continued leftward movement of slide 35 will further retract plunger 45 until it clears the O-ring 53, thereby admitting into chamber 48 a fresh charge of fuel from the carburetor bowl or float chamber 5 to replace that discharge therefrom by plunger action. Concurrently with retractive plunger movement from its extreme position, the choke valve will be moved by lever 30 and arm 27 toward its wide open position shown in Fig. 3 until finally the parts are at rest in the positions illustrated in these views.

I claim:

1. In a carburetor having an unbalanced choke valve tending to open responsive to unbalanced pressures and a primer, a single control having connections to the choke valve and the primer for the consecutive operation thereof, the connection of the control to the choke valve comprising a spring whereby the choke valve may open independently of movement of said control in a choke valve closing direction, a spring anchor and means interconnecting said anchor to said control for movement of the anchor in a direction to maintain substantially constant tension on said spring notwithstanding such movement of the control.

2. In a carburetor having an air inlet and a choke valve mounted in the carburetor adjacent the inlet and provided with an aperture, the combination with a choke valve actuator operatively connected with said valve for movement thereof between its open and closed positions, a primer pump comprising a cylinder, a plunger, and an injection tube from said cylinder to a position in front of said carburetor inlet and directed toward the choke valve aperture and motion transmitting connections from said actuator to said plunger mechanically actuating said plunger to inject fuel into said aperture in the same direction of actuator movement in which said choke valve is closed.

3. The device of claim 2 in which the operating connections between said actuator and the choke valve and plunger respectively include means whereby the plunger injects fuel through said aperture in a range of actuator movements which is subsequent to the range of actuator movements in which said choke valve is closed.

4. In a carburetor having a float bowl and an air inlet passage, a primer comprising the combination with a cylinder mounted directly on the carburetor and having a gravity-flow conduit leading to it from the bowl and communicating with the cylinder at an intermediate point, a plunger normally retracted in said cylinder to a position on one side of said point to leave said conduit in open communication with said cylinder and reciprocable to the other side of said point, a duct leading from said cylinder at said other side of said point and comprising a delivery pipe extending externally of the carburetor and directed into said air inlet passage and means for actuating said plunger from its normally retracted position across said point of communication and therebeyond to displace fuel trapped in the cylinder beyond the point of communication to effect the discharge thereof under pressure of the plunger through said pipe into said inlet passage.

5. The device of claim 4 in further combination with an annular seal fixed in said cylinder beyond said point of communication with the carburetor bowl to receive said plunger and through and beyond which said plunger advances for the discharge of fuel through said pipe.

6. In a carburetor having a float bowl and an air inlet passage, a primer comprising the combination with a cylinder communicating at an intermediate point with said bowl, a plunger normally retracted in said cylinder to a position above said point, a duct leading from said cylinder below said point and comprising a delivery pipe extending externally of the carburetor and directed into said air inlet passage and means for actuating said plunger from its normally retracted position across said point of communication and therebeyond to displace fuel trapped in the cylinder below the point of communication to effect the discharge thereof under pressure of the plunger through said pipe into said inlet passage, in further combination with a carburetor choke valve mounted for oscillation in the inlet passage and provided with an opening to admit air despite the closed position of said valve, said pipe being directed toward said opening to project fuel therethrough.

7. In a carburetor having a float bowl and an air inlet passage, a primer comprising the combination with a cylinder communicating at an intermediate point with said bowl, a plunger normally retracted in said cylinder to a position above said point, a duct leading from said cylinder below said point and comprising a delivery pipe extending externally of the carburetor and directed into said air inlet passage and means for actuating said plunger from its normally retracted position across said point of communication and therebeyond to displace fuel trapped in the cylinder below the point of communication to effect the discharge thereof under pressure of the plunger through said pipe into said inlet passage, in further combination with a carburetor choke valve having an actuator operatively connected with the actuating connections for said plunger and having connections to said valve, the respective connections to the valve and plunger comprising means for substantially closing the valve before the plunger advances beyond said point, whereby the choke valve and primer are sequentially effective upon the continuous movement of a single actuator.

8. In a carburetor having an air inlet passage, a fuel supply chamber having a nozzle leading to said passage and an apertured choke valve mounted in said passage in the path of air moving toward said nozzle, the combination of a cylinder mounted at the side of said chamber and communicating at an intermediate point with said chamber, a plunger reciprocable in the cylinder across and beyond said point of communication, means for sealing the plunger to the cylinder beyond said point, means providing a conduit leading from said cylinder beyond said point to a position forwardly of the carburetor and directed toward the position of the choke valve aperture in the closed position of the valve, an actuator provided with a mounting on said carburetor for forward and backward movement, an

actuating connection from the actuator to the choke valve for the movement of said valve between open and closed position, an actuating connection from the actuator to the plunger for the movement thereof between a normally retracted position and an advance position beyond said point of communication and beyond said sealing means from said retracted position, said connections comprising means whereby said choke valve and plunger are effective sequentially for choking and priming said carburetor.

10 9. The device of claim 8 in which the actuating connections from the actuator to the choke valve comprise lost motion connections for permitting continued advance of the plunger and actuator after the choke valve has reached its closed position.

15 10. The device of claim 8 in which said actuator comprises a slide for which said carburetor is provided with guide ways.

11. In a carburetor having a float chamber and an air inlet passage, a boss at the side of the float chamber provided with a cylinder, said boss and chamber having a passage leading from a lower portion of the float chamber into said cylinder at a point intermediate the ends thereof, a plunger normally retracted into one end of the cylinder, a discharge pipe leading from the other end of the cylinder to said air inlet passage, the said other end being substantially closed save for said pipe and adapted to receive fuel from said float chamber through said passage in the retracted position of the plunger, said cylinder having annular packing means adapted to receive and provide a seal for said plunger and disposed in the portion of the cylinder between said passage and the closed end thereof whereby the advance of said plunger in said cylinder in advance of said packing means will have no effect on the fuel in the cylinder, but advance of said plunger beyond said packing means will displace fuel positively from said cylinder through said pipe.

12. In a carburetor having a choke valve and an air passage, the combination with a positive displacement priming fuel pump and means providing a fuel discharge

40 line from said pump into said passage, of a choke valve for restricting air flow through said passage, means for actuating said valve, means for actuating said fuel pump to force a measured charge of fuel through said line into said passage, and a single control having means for the successive operation of the choke valve actuating means and the primer pump actuating means, said control having an impositive spring connection with said valve actuating means whereby said valve is closed impositively, said valve having an unbalanced rockshaft mounting upon 50 which said valve may open in opposition to said impositive connection, subject to air movement through said passage.

13. In a carburetor having an air passage, the combination with a rock shaft spanning the passage in an off center position and a choke valve having an unbalanced mounting on said rockshaft and movable in the oscillation of said shaft between an open position in which said valve is substantially parallel to air flow through said passage and a closed position in which said valve is transverse to the direction of flow and is subject to unbalanced pressures in the event of such flow, an arm on said rockshaft and a lever engageable with said arm in a valve opening direction, and a spring connecting the lever with the arm and comprising an impositive means for transmitting motion to said arm and for tensioning the spring and transmitting motion to said rockshaft in a valve closing direction, whereby said valve may open in response to unbalanced pressures thereon irrespective of the position of said lever, said lever having a positive connection with said arm for transmitting motion to said rockshaft in a valve opening direction.

14. In a carburetor having an air passage, the combination with a rock shaft spanning the passage in an

off center position and a choke valve having an unbalanced mounting on said rockshaft and movable in the oscillation of said shaft between an open position in which said valve is substantially parallel to air flow through said passage and a closed position in which said valve is transverse to the direction of flow and is subject to unbalanced pressures in the event of such flow, an arm on said rockshaft and a lever engageable with said arm in a valve opening direction and having an impulsive spring connection with said arm for transmitting motion to said rockshaft in a valve closing direction, whereby said valve may open in response to unbalanced pressures thereon irrespective of the position of said lever, said lever having a positive connection with said arm for transmitting motion to said rockshaft in a valve opening direction, in further combination with a manually operable control connected with said lever, a fuel priming pump having a fuel delivery pipe leading to said passage beyond said valve and motion transmitting connections from said control to said pump for the discharge of fuel into said passage subsequent to the closing of said valve, the said im-

10

5

15

20

positive connection between said lever and arm permitting continued movement of said control and lever for the actuation of said pump after said valve is closed.

15. The device of claim 14 in which said valve is provided with an air admission port and the fuel delivery conduit from said pump comprises a nozzle directed through said port into a portion of said passage beyond the valve.
